ADJUSTABLE PLATE CYLINDER FOR
PRINTING PRESSES

Alexander T. Koppe, New York, N. Y.

Application March 26, 1934, Serial No. 717,382

2 Claims. (Cl. 101—248)

This invention relates to improvements in printing presses and is particularly adapted for that type of press in which an inked impression carried by an offset press plate mounted on a 5 plate cylinder is transferred by a rubber blanket mounted on a transfer cylinder to a paper sheet carried by the rotating paper-carrying cylinder of the press. The principal object of the invention is to provide means for effecting the angular 10 adjustment of the plate cylinder about its axis of rotation in order to vary the position of the printed work on the paper sheet with respect to the edge of the sheet, without changing the position of the plate on the plate cylinder. A 15 further object of the invention is to provide a printing press having a plate carrying cylinder which is adjustable about the shaft on which it is mounted for the purpose of varying the position of the edges of the plate with reference to a contacting transfer cylinder. Still another object of the invention is to provide an improved clamping mechanism by which a cylinder of a printing press may be clamped on its shaft and readily adjusted 20 to any desired angular position. Other objects 25 relate to various features of construction and arrangement which will appear more fully hereinafter.

The nature of the invention will be understood 30 from the following specification taken with the accompanying drawings, in which one embodiment is illustrated. In the drawings,

Fig. 1 shows a vertical section transversely to the axes of the cylinders of a printing press of the offset type, showing the improved clamp of 35 the present invention applied to the uppermost cylinder and illustrating in a general way the means by which the paper sheets are fed to the paper-carrying cylinder;

Fig. 2 shows an enlarged section taken axially of 40 the plate carrying cylinder on the line 2—2 of Fig. 1; and

Fig. 3 is a perspective view of the improved clamp by which the plate carrying cylinder is secured upon its shaft.

As illustrated in Fig. 1, the invention is applied to a printing press comprising side frames 45 having mounted between them a plate cylinder 11, a transfer cylinder 12, a paper-carrying cylinder 13 and a delivery cylinder 14. The plate cylinder 11 is mounted upon a shaft 15 which is journaled at its ends in bearings carried by the side frames 10. This cylinder is adapted to carry 50 on its peripheral surface an offset press plate 16, of zinc or the like, which has one edge secured between clamps 17 and the other edge secured

between clamps 18 which are located within a longitudinal recess 11^a formed in the outer cylindrical portion of the cylinder. The press plate 16 is adapted to be inked by inking rollers 19 which are carried by a head 20, pivoted at 21 on the side frames 10 and adapted to carry an ink supply which is delivered to the rollers 19 through other rollers 22. The cylinder 11 rotates in the direction of the arrow 23 and the press plate 16 is adapted to contact with and transfer its inked impression to a rubber blanket 25 which is secured on the surface of the transfer cylinder 12 by means of clamps 26 and 27 which are located within a longitudinal recess 12^a formed in the cylinder.

The shaft 15 of the plate cylinder 11 has secured thereon a large gear 28 which meshes with a similar large gear 29 secured upon the shaft 30 which is journaled in the side frames 10 and which carries the transfer cylinder 12. By means of this connection, the cylinder 12 is caused to 15 rotate in the direction of the arrow 31 and the impression carried by the blanket 25 is adapted to be transferred to a paper sheet mounted upon the surface of the cylinder 13 which rotates in the direction of the arrow 32 and which is carried by 20 a shaft 33 journaled in the side frames. The paper sheets, when printed, are removed from the cylinder 13 by clamping devices 34 which are carried by endless chains 35 passing around the delivery cylinder 14. The paper sheets are delivered to the cylinder 13 from a table 36 by means 25 of suitable transfer mechanism which may be of the form described and claimed in my co-pending application Serial No. 700,258, filed November 29, 1933. This mechanism includes a supporting plate 36^a on which the forward portions 30 of the paper sheets are successively brought to rest with the forward edge of each sheet engaging a series of stops 37 mounted on a shaft 38. When these stops are elevated, the paper sheets 35 are moved by certain suction devices into engagement with the stops 38A which are carried by the cylinder 13, whereupon the gripping fingers 39, carried by the cylinder, are actuated to grip the paper sheet which is then carried around with 40 the cylinder 13 to receive an inked impression from the cylinder 12. The suction devices by which the sheets are moved into engagement with the stops 38A comprise a series of suction drums 40 which rotate with a hollow shaft 41, the interior of which is connected with a source of suction. Each drum 40 has a series of apertures in its peripheral portion which are connected with the interior of the hollow shaft 41 through 45 passages formed in stationary suction blocks 42, 50 55

When the stops 37 are elevated, the suction exerted through the blocks 42 and the openings formed in the peripheral portions of the drums 40 cause the paper sheets to be positively gripped 5 and moved until their forward edges engage the stops 38A, whereupon the suction is relieved and the paper sheet is released by the drums.

The present invention relates to the means by which the cylinder 11 is adjustably secured upon the shaft 15 and this mechanism is more particularly illustrated in Figs. 2 and 3. The cylinder 11 is rotatably mounted upon the shaft 15 and adjacent one end of the cylinder there is located the gear 28, previously referred to, which is secured against rotation on the shaft by means of a key 45 in addition to being held against endwise movement by means of a set screw 46 which engages a threaded aperture in the hub of the gear and bears against the surface of the shaft. The end of the cylinder 11 is reduced in diameter as shown at 11^b and there is fitted upon this reduced portion a bearing ring 47 which is adapted to bear on its peripheral surface against a similar ring mounted upon the adjacent cylinder 12 for the purpose of regulating the spaced relation of the axes of the two gears when they are in operative positions with respect to each other. The shaft 15 has reduced end portions which are journaled in roller bearings 48 each of which is retained against a shoulder in an aperture 10^a of the frame 10 by means of a ring 49 secured in place by screws 50. The end of the shaft 15, shown in Fig. 2, is threaded for engagement by a nut 51 and washer 52 and the aperture 10^a is closed at the outer side of the nut 51 by means of a cover plate 53 attached to the side frame by screws 54. The other end of the shaft 15 projects through the side frame and is connected to suitable driving mechanism by which the shaft is rotated when the press is in operation.

The cylinder 11 is secured in adjusted angular position on the shaft 15 by means of a clamp 55 having the form illustrated particularly in Fig. 3. This clamp has a hub portion 55^a which fits the shaft 15 and it is split transversely as shown at 55^b, the slot extending through both sides of the bearing portion 55^c and terminating at one end in an aperture 55^e which extends through the clamp and which is adapted to receive a headless screw 56 by which this end of the clamp is secured to the cylinder 11, within the hollow interior of the cylinder, the screw engaging threaded apertures in the end wall of the cylinder and in the adjacent bearing ring 47, as

shown in Fig. 2. At the side of the shaft opposite the screw 56, the clamp comprises spaced ears 55^d extending parallel to each other on opposite sides of the slot 55^b and having apertures 55^e therethrough for engagement by a clamping stud 57. The aperture 55^e in one of the ears 55^d is threaded for engagement by the threaded end of the stud 57 and by tightening this stud, the clamp may be caused to grip the shaft 15 for holding the cylinder 11 against rotation on the shaft. The clamp 55 is held against endwise movement on the shaft and on the screw 56 by means of a collar 58 which is secured on the shaft 15 by means of a set screw 59. By means of this construction, the clamp 55 may be employed for permitting the cylinder 11 to be adjusted to any desired angular position on the shaft 15, after which the clamp may be tightened to hold the cylinder in adjusted position, thus making it possible to locate the margin of the impression carried by the plate 16 at the desired point with respect to the rubber blanket on the cylinder 12 so that the printed matter will appear in the required location with respect to the paper sheet which is carried by the cylinder 13.

Although one form of the invention has been shown and described by way of illustration, it will be understood that it may be constructed in various other forms coming within the scope of the appended claims.

I claim:

1. The combination in a printing press, of a hollow plate cylinder, a rotatable shaft having said cylinder rotatably mounted thereon, means for rotating said shaft, and a clamp located within and secured to said cylinder, said clamp embracing said shaft for securing said cylinder in adjusted angular position on said shaft, said cylinder having a slot in its outer wall to permit access to said clamp.

2. The combination in a printing press, of a hollow plate cylinder having end walls connected by a cylindrical wall having a slot therein, a rotatable shaft having said cylinder rotatably mounted thereon, means for rotating said shaft, a separate split clamp located within said cylinder and embracing said shaft, a pin engaging one end of said clamp for securing it to one of said end walls, and means engaging the other end of said clamp for causing it to grip said shaft and thereby secure said cylinder in adjusted angular position on said shaft.

ALEXANDER T. KOPPE.
